PLOW BOTTOM

Herbert N. Baker, Syracuse, N. Y., assignor to
 Syracuse Chilled Plow Company, Inc., Syracuse,
 N. Y., a corporation of New York

Application October 6, 1941, Serial No. 413,755

17 Claims. (Cl. 97—125)

This invention relates generally to agricultural implements and more particularly to plows and other earth working tools.

The object and general nature of the present invention is the provision of certain new and useful improvements in plows of the type having a detachable and replaceable point, and it is also an important feature of this invention to provide a novel point particularly constructed to facilitate attaching the same and to improve the operating efficiency of the point.

More specifically, it is a feature of this invention to provide a plow having a separate wing, the landside edge of which is spaced from the landside face of the frog to which the wing and moldboard are attached, with a detachable and replaceable point and clamping means carried by the frog and having a wedging action against the point and reacting against the frog for, first, drawing the replaceable point into proper position and holding the same in that position, and second, to establish a lateral clamping action between the point and the landside face of the frog, whereby the detachable point may be held firmly and rigidly in position. In this connection, it is a further feature of this invention to provide improved clamping means of the wedge type which not only draws the point into proper position, generally longitudinally of the frog, but also forces the point generally laterally against the adjacent edge of the wing or blade.

Still further, it is a feature of this invention to provide a plow of the separate wing and detachable point type, in which the adjacent and substantially contacting edges of the wing and point are beveled, whereby the adjacent portion of the point overlies the beveled edge of the wing or blade. In this connection it is also a feature of this invention to provide a lateral extension on the point which is formed to overlap the junction between the wing and point so as to prevent roots and the like from entering the space between the point and wing or blade.

These and other objects and advantages of the present invention will be apparent to those skilled in the art after a consideration of the following detailed description, taken in conjunction with the accompanying drawing.

In the drawing:

Figure 1 is a plan view of a plow bottom in which the principles of the present invention have been incorporated;

Figure 2 is a fragmentary enlarged bottom view, showing in particular the detachable point

and the clamping wedging means securing the point to the plow bottom frog in overlapping relation with respect to the adjacent portion of the wing or blade;

5 Figure 3 is an enlarged section taken generally along the line 3—3 of Figure 2;

Figure 4 is an enlarged fragmentary perspective view of the wedge end of the drawbolt shown in Figures 2 and 3;

10 Figure 5 is a bottom view of the detachable point; and

Figure 6 is a section taken through the point substantially on the line 6—6 of Figure 5.

Referring now to the drawing, more particularly to Figures 1 and 2, the plow bottom I have chosen to illustrate the present invention is indicated in Figure 1 in its entirety by the reference numeral 1 and comprises a construction that is more or less conventional, including a frog 2 which serves as the supporting means for the other parts, a moldboard 3 and a landside 4, connected by a brace 5. The plow bottom I also includes a wing or blade 6 which preferably is connected to the frog 2 by a pair of plow bolts 7 so as to form a continuation of the moldboard surface. The wing or blade 6 includes a landside edge 9 which is spaced laterally from the landside face of the moldboard and landside, indicated by the reference numeral 11. The landside portion of the frog 2 is indicated in Figure 2 by the reference numeral 12, and the edge of this portion of the frog lies in or adjacent the plane of the landside face 11 mentioned above.

According to the principles of the present invention I provide a separate detachable and replaceable plow point or share indicated in its entirety by the reference numeral 15. The point 15 is of particular construction and is designed to be detachably connected to the frog 2 so as to lie in the space between the landside edge of the wing 6, the forward edge of the moldboard 3 at the landside portion thereof, indicated by the reference numeral 16, and the landside plane of the plow bottom I. Preferably, the detachable point or share 15 is of cast construction, embodying a wedge shaped point proper, indicated by the reference numeral 17, this portion being formed at the forward end of a thickened blade section 18. The landside edge of the point 15 is formed with a landside flange 19 that extends rearwardly to the rear end of the detachable point 15, and the section of the point 15 rearwardly of the thickened portion 18 is formed of thinner stock and is formed on a gentle curve. This section of the point 15 is indicated in Figure 5 by

the reference numeral 21, and joins the landside flange 19 at an oblique angle, as best shown in Figure 6.

The edge of the detachable point 15 that engages the edge 9 of the blade or share 6 is beveled, as indicated at 22, for the major portion of its length, the beveled edge 22 terminating forwardly in a lateral projecting section 23 to which reference will be made below. The blade edge 9 is also beveled so that when in position the beveled edge 22 of the detachable point 15 overlies the beveled edge 9 of the wing or blade 6. The relation of the blade or wing and the detachable point or share 15 is indicated in Figure 6, and as shown in Figure 2, the lateral extension 23 of the point 15 overlaps, or lies directly in front of, the junction between the adjacent beveled edges 9 and 22, whereby the lateral projection 23 on the point 15 serves to guard the space between the point on the wing or blade and prevents roots or the like from being forced in between the wing and point.

Improved means is provided for holding the detachable point 15 in the frog 2. The frog includes vertical sections 2a and 2b, the section 2a lying laterally inwardly of the edge 12 by a small amount, as best shown in Figure 2. The point 15 is provided with a pair of projecting lugs 26 which, as best shown in Figure 6, are disposed a distance from the under surface of the portion 21 of the point 15 which is substantially equal to the thickness of the edge portion 12 of the frog 2. The forward portion of the frog forms what is termed a "toe," and this portion of the frog is adapted to receive the point 15, with the edge 12 disposed between the section 21 of the point and the lugs 26, as best shown in Figure 2. At the side of the point 15 opposite the lugs 26, an undercut lug 29 is disposed. Preferably, the lug 29 is formed integral with the point 15, but if desired, the lugs 29 may be separately formed and attached to the point 15 by any suitable means. The lug 29 includes an undercut face 31, which makes an oblique angle with the under surface of the adjacent portion 21, as best shown in Figure 6, and the undercut surface 31 is disposed in a plane which, as best shown in Figure 5, extends at an oblique angle to the landside plane of the point 15 and also to substantially the same angle with respect to the beveled edge 22, which preferably is parallel to the landside flange 19, or substantially so.

The lateral flange 2b (Figure 2) of the frog 2 is provided with an opening 35 (Figure 3), and back of the flange 2b the frog 2 carries a bracket 36, the upstanding portion 37 of which is apertured and the other portion 38 of which is welded to the frog 2. Preferably the frog 2 is of welded steel construction, but if desired, the frog 2 may be made of malleable iron or cast iron, in which case the lug 36, the flange 2b and/or other parts may be integral. A drawbolt 40 extends through the opening 35 in the flange 2b and the opening in the bracket portion 37. One end of the drawbolt 40 is threaded and receives a nut 41. The other end of the drawbolt, as best shown in Figure 4, is welded to a triangular block 43 that is formed with an undercut wedging surface 44. The plane of the surface 44 extends at an angle to the axis of the drawbolt, which is disposed generally parallel with respect to the sides of the point 15, as best shown in Figure 2, although this is of course not essential.

As best shown in Figures 2 and 3, the frog 2

is formed with an opening 45 extending therethrough, and the side or edge 46 of the opening 45, nearest the landside edge of the point, serves as a shoulder against which the longer edge 47 (Figure 4) of the drawbolt wedge block 43 is adapted to bear, and in the preferred construction, the wedge block 43 as well as the lug 29 on the point 15 extends into the frog opening 45 when the parts are in assembled relation.

When the drawbolt 40 is tightened, the cooperating undercut surfaces 31 and 44 engage and the block 43 reacts against the shoulder 46 to draw the point 15 generally rearwardly on the toe of the frog 2, with the lugs 26 disposed on the underside of the frog edge 12, and at the same time the angularity of the surfaces 31 and 44 is such that the point 15 is also drawn or forced generally laterally inwardly, forcing the beveled edge 22 of the point against the cooperating beveled edge 9 of the wing or blade 6. Further, since the cooperating surfaces 31 and 44 are undercut, the drawbolt 40, which contacts the lower surface of the frog 2, effectively holds the point 15 down against the upper part of the frog. Thus, with one drawbolt, I am enabled to clamp the point 15 onto the frog from three directions, namely, rearwardly, laterally, and generally vertically downwardly against the frog 2. Forcing the beveled surface 22 of the point against the edge 9 of the wing 6, not only holds the latter downwardly and prevents the point from curling upwardly in case there is any tendency for the soil pressure to push the wing 6 upwardly, but also the lateral extension 23 of the point is disposed in front of the joint between the wing and point thereby preventing roots and the like from being forced into the space between the wing and point.

When it is desired to remove the point 15, as to replace it, the nut 41 of the drawbolt is loosened enough to allow the wedge end of the bolt to be moved to the forward end of the hole 45 in the frog. As best shown in Figure 2, this end of the hole 45 is reduced in width, as indicated at 45a, so that the bolt 40 is prevented from rotating about its longitudinal axis. It will also be noted from Figure 2 that the opening 45 is provided with a rear wider portion, as indicated at 45b. The purpose of this arrangement is to permit the withdrawal of the drawbolt 40 easily and conveniently after the share 15 has been removed. With the share or point 15 removed, the drawbolt can be moved rearwardly to carry the wedge block 43 into the wider section 45b, and then the drawbolt can be rotated 180 degrees after which it may be withdrawn completely from the frog.

While I have shown and described above the preferred structure in which the principles of the present invention have been incorporated, it is to be understood that my invention is not to be limited to the particular details shown and described above, but that, in fact, widely different means may be employed in the practice of the broader aspects of my invention.

What I claim, therefore, and desire to secure by Letters Patent is:

1. A plow bottom comprising a frog, a point adapted to be mounted on the upper face of said frog with a portion disposed against the landside face of the frog, a draw bolt mounted on the frog on the lower face thereof, and cooperating wedge lugs carried by said draw bolt and on the lower face of said point, said lugs having cooperating undercut surfaces, whereby tightening the draw

bolt serves to hold the point down against the upper face of said frog, and said cooperating surfaces being disposed at an angle to the plane of the landside face of said frog, whereby tightening said draw bolt serves to force said part of the point laterally against the landside face of the frog.

2. A plow body comprising a frog having a landside edge, a wing secured to said frog and having a beveled edge spaced from the landside edge of the frog, a separate point formed at one side with an overhanging portion engaging said landside edge of the frog and at the other side with a beveled edge overlying the beveled edge of said wing, and means having a laterally directed component of force for clamping the overhanging portion of the point against the landside edge of the frog and the beveled edge of the point against the beveled edge of the wing.

3. A plow body comprising a frog having a landside edge, a wing secured to said frog and having a beveled edge spaced from the landside edge of the frog, a separate point formed at one side with a landside portion adapted to engage said landside edge of the frog and at the other side with a beveled edge adapted to overlie the beveled edge of said wing, said point being free for movement relative to said frog when the landside portion of the point engages the landside portion of the frog, and means acting between the frog and point for forcing the latter generally laterally so as to hold said beveled edges in substantial contact when the point is moved longitudinally of the frog.

4. A plow body comprising a frog having a landside edge, a wing attached to the frog and having an edge parallel to but spaced from said landside edge of the frog when the wing is attached to the frog, a replaceable point detachably secured to the frog in a position against the edge of said wing that is parallel to said landside edge, thereby providing for movement of said point along said parallel edges, said point having a portion disposed laterally beyond the plane of said edge of the wing so as to prevent roots and the like from entering the space between the point and the wing, and means for shifting said point along said parallel edges for clamping said point to said frog with said lateral portion in front of said wing edge.

5. A plow point having a beveled wing-engaging edge at one side adjacent the rear end and a portion at the other side adapted to engage the landside face of a frog and disposed generally parallel with respect to said wing-engaging edge, said point also having a laterally directed extension at said one side forward of said beveled wing-engaging edge disposed laterally beyond said wing engaging edge so as to overlie the junction between the wing and point along said beveled edge.

6. A plow point having a beveled wing-engaging edge at one side adjacent the rear end and a portion at the other side adapted to engage the landside face of a frog, said portions being substantially parallel, and a drawbolt receiving lug on the point and having a wedging surface disposed at an angle to said frog-engaging portion and said wing-engaging edge.

7. A plow point comprising a member having at one side a depending landside flange extending at an oblique angle toward the opposite side and at the opposite side a wing-engaging edge and an extension disposed in front of and extending laterally beyond said edge.

8. The combination with a plow body of a detachable point having a landside flange and an abutment on its lower face, a frog having a projecting toe portion fitting between said abutment and said flange, said point having a part extending beneath said toe portion, and means connected between the frog and said abutment on the point for drawing the latter onto the plow body both generally longitudinally of the toe portion of the frog and generally laterally against the side of the toe portion for securing the point to the plow body.

9. The combination with a plow body of a detachable point having a landside flange and an abutment on the inner face of said landside flange, a frog having a projecting toe portion fitting between said abutment and said flange, and means on the frog having a lateral wedging action against the point for drawing the latter onto the toe portion of the frog and clamping the point laterally against the side of the toe portion of the frog.

10. In a plow body, a frog having a lug-receiving opening and an abutment face, longitudinally movable securing means carried by said frog and including a wedge lug having a portion slideable along said abutment face, a point detachable relative to said frog and having a part engageable with the landside face of the frog, and a wedge lug on said point adapted to be engaged with the wedge lug on said securing means, at least one of said wedge lugs extending into said frog opening to receive the other wedge lug, and said wedge lugs having complementary engaging surfaces formed so that the lug on said securing means reacts against said abutment face for clamping said point on said frog against the landside face of the latter.

11. In a plow body, a frog, securing means movably carried thereby and having at one end a lug formed with an undercut clamping surface disposed at an angle to the line of movement of said securing means, and a point adapted to be secured to said frog with a part against the landside face of the latter and carrying a lug having an angled undercut surface adapted to receive the undercut surface of the lug on said securing means, whereby tightening the latter holds said point on the frog and also clamps said point against the landside face of the frog.

12. The combination with a plow body of a detachable point having a landside flange, a frog having a projecting toe portion fitting against said flange, said point having a part extending beneath said toe portion, and means connected between the frog and said point for drawing the latter onto the plow body both generally longitudinally of the toe portion of the frog and generally laterally against the side of the toe portion for securing the point to the plow body.

13. The combination with a plow body of a detachable point having a landside flange and an abutment on its lower face, a frog having a projecting toe portion fitting between said abutment and said flange, and means connected between the frog and said abutment on the point for drawing the latter onto the plow body both generally longitudinally of the toe portion of the frog and generally laterally against the side of the toe portion for securing the point to the plow body.

14. A plow body comprising a frog having a landside edge, a wing secured to said frog and having a beveled edge spaced from the landside edge of the frog, a replaceable point formed

at one side with a landside portion engaging said landside edge of the frog and at the opposite side with a beveled edge overlying the beveled edge of said wing, and means acting between said frog and said point for drawing said other side thereof down against said beveled wing edge and drawing said landside portion generally laterally against said landside edge of the frog.

15. A plow point having generally parallel sides, a flange at one side with means for engaging the landside portion of a frog, said flange having a projection overlapping said landside portion and engaging the under side of said landside portion, when said plow point is mounted on said frog, for holding that side of the point down against said frog, a beveled wing-engaging portion at the opposite side of said point, and a fastener-receiving part on the lower side of said point and adjacent said beveled portion for receiving means for holding said beveled portion down against said frog.

16. A plow point having a wing-engaging edge

at one side adjacent the rear end and a flanged portion at the opposite side engaging the landside face of a frog, when the plow point is mounted on a frog, said flanged portion having a part 5 engaging the underside of the landside part of said frog, and a drawbolt receiving lug on the point and having a wedging surface disposed at an angle to said frog-engaging portion and said wing-engaging edge.

10 17. A plow point adapted to be attached to a frog, comprising a wedge shaped member having a thickened soil-entering blade section, a rearward section thinner than said blade section and receiving said frog with an edge of the 15 frog disposed adjacent the thickened rear edge of said blade section, a flange extending along one side of said member from said blade section toward the rear edge of said thinner section and engaging one side of said frog, and lug 20 means on said flange engaging the underside of said frog.

HERBERT N. BAKER.
